UNITED STATES PATENT OFFICE

2,499,687

CONDIMENT AND TOOTHPICK HOLDER

Lloyd A. Smith, Washington, D. C.

Application May 13, 1946, Serial No. 669,377

1 Claim. (Cl. 206—1)

1

This invention relates to condiment holders and more particularly to a combined holder for several different condiments and other articles as toothpicks.

An object of this invention is to provide a condiment holder which is so constructed that several condiments as salt and pepper may be separately contained in a single dispenser and to provide for holding other useful articles as toothpicks in a container between the other compartments.

Another object of this invention is to provide a transparent condiment and toothpick holder having a removable base which is attached to the body of the holder by a resilient clamp fixed to the base and to provide a spring pressed cover for the tooth pick compartment.

Still another object of this invention is to provide a transparent condiment and toothpick holder made of plastic or other suitable material wherein the several condiments are contained in the same body, being separated by a vertical wall, a portion of the vertical wall forming a recess in which toothpicks or similar articles may be stored, and a spring pressed cover for the recess.

With the above and other objects in view, my invention consists in the arrangement, combination and details of construction disclosed in the drawings and specification, and then more particularly pointed out in the appended claim.

In the drawings,

Wherein similar reference characters designate similar parts throughout the respective views,

Figure 1 is a top plan view of a condiment and toothpick holder constructed according to an embodiment of this invention,

Figure 2 is a vertical sectional view taken on the line 2—2 of Figure 1,

Figure 3 is a vertical sectional view taken on the line 3—3 of Figure 2,

Figure 4 is a horizontal sectional view taken on the line 4—4 of Figure 3,

Figure 5 is an enlarged detail view, partly broken away and partly in section, of the spring and hinged cover.

Referring to the drawings, the numeral 10 designates generally the body of a combined condiment and toothpick holder constructed according to an embodiment of my invention. The body 10 is formed of a hollow transparent body, substantially elliptical in cross section, which is closed at the upper end with an outer layer or cover 11 which is fixed to or formed on the body 10, and is open at the lower end.

A vertical central wall 12 is fixed between the inner sides of the body 10 and extends upwardly

from the bottom edges substantially past the vertical center of the body 10 and is continued upwardly to the top of the cover 11 by a pair of spaced apart vertical walls 14 connected together at their lower end and to the wall 12 by a horizontal bottom forming member 15. The cover 11 is formed with an opening 16 between the vertical walls 14 whereby an upwardly opening receptacle 17 is formed within the body 10 above the central wall 12 an outer layer or cap 11a extends over the cover 11 and has downwardly directed flanges engaging within the opening 16. A second pair of vertical walls 18 are fixed between the walls 14 and extend upwardly from the bottom forming member 15 to provide internal end walls for the receptacle or compartment 17.

The walls 12 and 14 divide the body 10 then into three compartments or sections 17, 19 and 20. The cover 11 and outerlayer 11a are further formed with openings 21 in the opposite sides thereof which open into the sections 19 and 20 for dispensing salt and pepper or other suitable material from their respective compartments.

For holding the material in the sections 19 and 20, there is provided a flat base 22, also made of plastic, substantially wider than the body 10 and having an upwardly extending flange 24 extending from the top thereof for engagement about the outer sides of the lower open end of the body 10. A pair of spaced apart opposed resilient clamping members 26 are fixed to the center of the base 22 and are adapted to frictionally engage the lower end of the wall 12 therebetween for clamping the base 22 to the body 10. The members 26 are substantially L-shaped being fixed to the base 22 by rivets 27 or other suitable fastening means through the lower arm thereof. The upwardly extending arms are flared outwardly at their upper end to provide for readily sliding the wall 12 between the opposed members 26.

Extending above the layer 11a and over the opening 16 an inverted U-shaped arcuate cover 28 is hingedly secured. The cover 28 is hingedly fastened by a pintle 29 which extends through the lower ends of the side walls of the cover 28 and a pair of laterally spaced apart ears 30 on the layer 11a. A curved cover operating lever or handle 31 is formed on the cover 28 and extends from the opposite side of the pintle 29 so that downward movement on the handle 31 will raise the cover 28 to open position. The cover 28 is constantly urged to closed position by a spring 32 coiled about the pintle 29, one end of which spring engages the lower side of the handle

31 and the other end engaging the outside of the body 10.

Thus there is provided a condiment holder having two downwardly opening compartments and an upwardly opening compartment, a cover for the lower end, and a spring pressed cover for the upper end.

I do not mean to confine myself to the exact details of construction herein disclosed, but claim all variations falling within the purview of the 10 appended claim.

Having thus described my invention, what I claim is:

A combined condiment and article holder comprising a hollow tubular body, a vertical central wall in said body having the upper end thereof terminating intermediate the length of said body, an elongated flat transverse member fixed to said upper end and having the opposite ends thereof engaging said body, a pair of spaced apart vertical walls extending upwardly from the opposite side edges of said transverse member, an arcuate end wall at the top of said body, a rectangular central opening in said end wall having the edges thereof formed integral with the upper ends of said spaced apart walls, an outer cap covering said end wall and formed with depending flanges thereon frictionally engaging said tubular body, a downwardly flanged opening in said cap communicating with said central end wall opening, 30 a substantially U-shaped closure member having vertical side walls formed with arcuate cut-outs in the lower edges thereof for closing engagement with said cap around the marginal edges of said

5 flanged opening, pivot means extending through said closure member and said cap for pivotally mounting said cap, and resilient means disposed between said cap and said closure member for constantly urging said closure member into closing engagement with said cap.
